UNITED STATES PATENT OFFICE

JAMES F. PATTON, OF CLEVELAND, OHIO

METHOD OF AND MECHANISM FOR TAPPING ARTICLES

Application filed June 27, 1927. Serial No. 201,648.

This invention relates, as indicated, to method and apparatus for tapping articles and refers more particularly to a new and improved tapping machine wherein blanks are continuously fed to a suitable holder and are automatically operated upon in such position by the threading device, each of the several operating elements of the machine being actuated automatically and continuously.

My invention contemplates the provision of an automatic machine of the present type having a horizontally or longitudinally arranged tapping tool, which tool is provided at one end with thread-cutting elements and has its other end constructed for the engagement of a detachable support. I am acquainted with the present well-known types of tapping machines, in which is employed an elongated tap having one end thereof provided with a bent portion which cooperates with a complementary curved recess in the supporting elements of the machine to prevent not only rotation of the tap, but also longitudinal displacement thereof. In such types of machines the articles to be threaded are carried in a revolving head which moves axially of the threading tool, these articles after being threaded passing beyond the actual threading elements of the tool and being carried along the shank thereof and discharged from its opposite end. Not only is the cost of these bent taps quite considerable, but the use thereof necessitates the non-revolving of the tap. The present invention primarily permits either the rotation of the tap or of the articles, as well as permitting the use of a straight tap.

An object of this invention is to provide a novel work-carrying head which is adapted to grip in alignment two or more articles to be threaded and to so design the operating mechanisms of the machine that the tap will be actuated in its longitudinal movement through its threading engagement with the article held in such head nearest the tap. A further object of the invention is to provide in such work-carrying head suitable work-gripping means which are intermittently actuated by each cycle in the op-

eration of the machine. In its simplest form the invention comprises the provision of a work-carrier having a pair of gripping jaws adapted to hold two articles in parallel spaced alignment and mechanism which discharges one of such articles from the carrier and at the same time positions the other article in the place of the discharged one. Such mechanism is also adapted to simultaneously insert a fresh article in the position of the second article. At the starting point in the cycle of operation of the present machine the tap is threaded into, and projects through, the article held in the carrier adjacent such tap and during the subsequent operations the tap is fed forward, on account of such threading engagement, into the other article held in the carrier. At the completion of the cycle of operation the tap is moved through the first of such articles beyond its threading elements and into the second one a distance comparing to its relationship with the first article at the start of the operation. Thereafter the tap is retracted to starting position, carrying with it the article engaged by its threading elements and the machine is ready to start another cycle in its operation.

A further object of the invention is to provide mechanism for engaging the free end of a tap during the threading operation of the machine. This mechanism may be so designed that in the case where the work holder is revolved the tap will be held stationary during threading operation, or, if the work holder is held from rotation suitable driving devices may be provided cooperating with such tap engaging mechanism for revolving the same. My invention also contemplates the provision of a stripping device which is engaged about the end of the tap adjacent the free end thereof and such mechanism is designed to cooperate with the tap holding mechanism so that when the latter is disengaged from the end of the tap such stripper will automatically discharge threaded articles which have traversed the tap shank from the threading position.

A still further object of the invention is to provide in connection with a hopper, an automatically operated shank feeding mechanism

which is actuated simultaneously with the release of the gripping mechanisms carried in the carrier head to feed blanks from such hopper to the carrier head.

5 Another object hereof is to provide a tapping machine of the present improved character wherein each of the several operating elements are actuated continuously and in timed relation with each other and to provide 10 adjustments in said several operating elements to adapt the machine for a wide range of usage.

To the accomplishment of the foregoing and related ends, said invention, then, consists of the means hereinafter fully described and particularly pointed out in the claims; the annexed drawings and the following description setting forth in detail certain mechanism embodying the invention, such 20 closed means constituting, however, but one of various mechanical forms in which the principle of the invention may be used.

In said annexed drawings:—

Fig. 1 is a front elevational view of a preferred embodiment of my invention;

Fig. 2 is a rear elevational view of the same;

Fig. 3 is a longitudinal central sectional view taken on the line 3—3 of Fig. 2;

25 Fig. 4 is a transverse vertical sectional view on an enlarged scale of the work chuck or carrier as taken on line 4—4 of Fig. 2;

Fig. 5 is a longitudinal vertical sectional view of the same taken on line 5—5 of Fig. 4;

30 Fig. 6 is a transverse vertical sectional view taken on line 6—6 of Figs. 1 and 2 in the direction of the arrows;

Fig. 7 is a longitudinal vertical section taken on line 7—7 of Fig. 6;

45 Fig. 8 is a fragmentary detail view of certain of the elements illustrated in Fig. 7 showing the same in a different operative condition;

Fig. 9 is a detail view of the drum operating latch;

Fig. 10 is a transverse vertical sectional view taken on line 10—10 of Fig. 1;

Fig. 11 is a similar view taken on line 52 11—11 of Fig. 1; and

Figs. 12 to 15, inclusive, are diagrammatic views illustrating in sequence the essential steps in the operation of one complete cycle of the present machine.

I have illustrated in the accompanying drawings a preferred embodiment of this invention which comprises a bed plate 1 mounted on a suitable support or legs 2 and having a number of vertical standards or projections carried on its upper surface. Certain 55 of these standards, designated in the drawings by numerals 3 and 4, are adapted to provide longitudinal supports for the revolving spindle, the blank feeding mechanism, the cam drum and other operating elements, as 60 will appear more fully hereinafter, and may

be either formed integrally with such bed plate or secured thereto by suitable bolts or like connections. A power shaft 5, which may be driven from any suitable source, is journalized in the standard bore and has mounted thereon a worm 6 meshing with a worm wheel 7 secured to the spindle 8. This spindle 8 is arranged longitudinally of the machine, having suitable bearing in the standard 4, and carries at one end the work or blank-carrying head 9. A cam drum 10 is carried at the other end of the spindle. 70 75 75

The work-carrying mechanism

Referring now to Fig. 3 the spindle 8 is shown in the form of a hollow or tubular shaft provided at its forward end with an enlarged portion 11, to which the spindle shank 12 of the work-carrying head may be secured by screw threads 13. The inner diameter 14 of the spindle 8 is sufficient to permit the articles worked upon to freely pass therethrough. In this figure is also seen the relative position of the worm wheel 7 and the tapping tool 15, which latter member is to be described more fully hereinafter. 20 25 30

Proceeding now to a more detailed description of the work carrier, the spindle shank 12 referred to above is formed at the rear end of the head proper and is provided with a central bore 16 of equal diameter to the interior 14 of the spindle 8. In Figs. 4 and 5 the work-carrying head 9 consists of an annular body member, carrying in its interior certain work-gripping mechanisms which, as has been previously stated, are actuated automatically to grip two or more articles in alignment. This gripping mechanism consists of a relatively fixed jaw or block 17 received in an annular recess 18 provided at the center of the head 9 and having formed at its inner periphery a plurality of serrations 19. Cooperating with the fixed jaw 17 is one or more movable jaw members 20, these latter jaws being carried in recesses 21 formed transversely of the head 9. Recesses 21 may be formed in any desired manner in the work-carrying head and are extended clear through such head to provide for the reciprocation of the jaws 20. Serrations 22 are provided on jaws 20 upon an inclined surface 23 formed on the side thereof adjacent the center of the head 9. A compression spring 24 is positioned in a recess 25 formed in one end of each jaw to lie between such member and the exterior of an annular ring 26 secured to the outer periphery of the work carrying head 9. The function of these springs obviously tends to normally force the jaws 20 inwardly toward the fixed jaws 17 and thus engage the work, herein shown as annular coupling members 27. The other ends of the reciprocating jaws 20 are received in a reduced portion 28 of the recess 21 and are provided with inclined or cam surfaces 110 115 120 125 130 135 140 145 150 155 160 165 170 175 180 185 190 195 198 200 205 210 215 220 225 230 235 240 245 250 255 260 265 270 275 280 285 290 295 298 300 305 310 315 320 325 330 335 340 345 350 355 360 365 370 375 380 385 390 395 398 400 405 410 415 420 425 430 435 440 445 450 455 460 465 470 475 480 485 490 495 498 500 505 510 515 520 525 530 535 540 545 550 555 560 565 570 575 580 585 590 595 598 600 605 610 615 620 625 630 635 640 645 650 655 660 665 670 675 680 685 690 695 698 700 705 710 715 720 725 730 735 740 745 750 755 760 765 770 775 780 785 790 795 798 800 805 810 815 820 825 830 835 840 845 850 855 860 865 870 875 880 885 890 895 898 900 905 910 915 920 925 930 935 940 945 950 955 960 965 970 975 980 985 990 995 998 1000

29, which lie in the path of an actuating cam slide 30.

The head 9 is provided with a longitudinal recess 31, in which is movably carried the 5 slide 30, such recess 31 being arranged to communicate with the upper ends of recesses 28. The ring 26 referred to above may be press fitted, or secured in any suitable manner, to the head 9 and an end plate 33 secured to the 10 forward end of the head 9 to prevent displacement of such ring and also of the jaw 17.

The inner side of cam slide 30 is formed with a plurality of inclined or cam surfaces 34 which cooperate with the cam surfaces 29 15 on the movable jaws 20 to actuate the latter upon movement of such slide. The rear end 35 of the cam slide 30 is projected beyond the exterior of the head 9 and is secured by a nut 36 to a grooved collar 37. This collar 37 as 20 best seen in Fig. 5 is slidably mounted on the head spindle 12 and is engaged by shoes 38, which ride in the groove 39 of the collar. Pivotally mounted upon the bed of the machine about a stud 40 is an encircling yoke 25 member 41, in the sides of which are secured pins 42 by which the shoes 38 are carried. At the upper end of the yoke 41 is secured a cam projection 43, which is adapted to be engaged by suitable mechanism to be present- 30 ly described to rock the yoke about its pivot, and consequently move the cam slide 30 relatively of the work head 9. It will be apparent from the foregoing that the couplings 27 are normally gripped between the jaws 17 and 20 and that upon actuation of the yoke 41 the jaws 20 will be moved against the springs 24, and thus free the couplings.

A feature in the construction of the work-gripping jaws consists in the particular shape 40 of the serrations 19 and 22. While the jaw 17 has been referred to as fixed, this member is received in the recess 18 in the head and confined therein by the end plate 33 and is permitted of a slight oscillatory movement. 45 The serrations 22 as seen in Fig. 4 are so formed that when engaged with the blanks 27 they tend to draw the jaws 20 inwardly of the head to more tightly engage with such blanks. In the operation of the machine it 50 will of course be understood that the blanks 27 are acted upon by the threading tool or tap 15, and on account of such threading operation the blanks will tend to rotate within the head 9. This rotary tendency of the blanks 55 causes the jaws 20 to be drawn into more firm engagement therewith on account of the construction of the serrations 22 as described, the jaw 17 permitting the slight oscillatory movement referred to to eliminate the dis- 60 figurement of the exterior of the work. As the jaws 20 are drawn into the head through the engagement of the blank therewith the jaw 17 moves slightly within the bore 18 until such engagement has become possible. 65 If the jaw 17 were not movable the blanks 27

would be forced around the serrations 19 and therefore become marred. The same advantages occur in the disengagement of the jaws 20 with the blanks in that as such jaws are moved to disengage the work they tend to rotate the blanks 27, and through such action the jaw 17 may be oscillated in the opposite direction until such blank has become entirely free.

As pointed out in the brief summary of the present invention at the beginning of the specification the work-carrying head is adapted to hold in operative position two or more blanks and the threading tool is preliminarily engaged with the blank nearest thereto. 70 During subsequent operations of the machine such tool is caused to move into the other blank and cut threads thereon. To provide suitable lubricant for the threading tool which performs its work within the head 75 9, inasmuch as lubricant supplied to the exterior or front end of the head would be practically ineffective, I have devised the novel mechanism which will now be described. Surrounding the ring 26, and retained thereon by the outwardly projecting ribs 45, is an annular recessed member or ring 46. The inner periphery of this ring 46 is recessed at 47 and is adapted to provide an oil reservoir therein between rings 46 and 20 80 90 95 26. In Figs. 1 and 3 is illustrated a conduit 48 which may be connected to any suitable source of lubricant supply, such as the ordinary oil pumps provided on automatic machinery. Provided in the head 9 is a plurality of radial apertures 49 which communicate the inner bore 18 through aligned apertures 49a with the recess 47. The jaw 17 is formed, as indicated at 51, with an oil groove in its outer surface by which the lubricant 105 forced through the holes 49 will be fed to the tapping tool at the interior of the head. The lubricant so introduced to the tapping tool not only serves to lubricate the same in its threading operation, but on account of the force of the oil will serve to extrude or carry toward the front of the work-carrying head the metal chips incidental to the threading operation, and in this way eliminate all 110 danger of the jaws becoming clogged. 115

The work-feeding mechanism

The mechanisms for feeding blanks to the work-carrying head may of course be varied in details, depending upon the character of the articles to be threaded, the form of such mechanism illustrated in the drawings being found acceptable to carry out such desired function in connection with hollow tubular articles. These articles, as has been 120 indicated, consist of couplings which are to be threaded the entire length of their inner surface. A gravity feed trough or chute is indicated at 50 in Fig. 11 and provides a 125 suitable guide for conveying the blanks one 130

at a time to a position in axial alignment with the center of the work-carrying head. The upper end of this chute may be connected to any desirable form of hopper by which the blanks are automatically fed thereto. The lower end 51 of the chute is formed to provide a bottom portion against which the lowermost blank rests, and in this position is in such coaxial alignment with the tapping mechanism. Extending from one side of the chute in coaxial alignment with the work-carrying head is a tubular projection 52 which is received in an aperture in the bracket 3. By this construction the chute is supported in proper position and may be adjusted relatively to the face of the work-carrying head by sliding the projection 52 within the bracket 3.

Operating longitudinally of the machine and in coaxial alignment with the spindle axis is a feed or push rod 54, which rod is adapted to slidably fit the interior 55 of tubular projection 52 and to have its forward end 56 terminate adjacent the end 51 of the blank chute. Suitable mechanism in the form of a bracket 57 secured to the outer end of rod 54, and also to an operating shaft 58, is provided for actuating such rod in its feeding function. The end 56 at its exterior is provided with a reduced shoulder 59 which is adapted to loosely fit the interior of the coupling 27 so that as the rod 54 is reciprocated to feed the couplings from the chute to the work-carrying head they are supported in proper alignment. In operation, after the tap has been threaded into the outermost article held in the head 9 the rod 54 is moved through the agency of shaft 58, as will appear more fully hereinafter, to the left of Fig. 2 until the end 59 is beyond the vertical plane of the chute 50. At this time one coupling 27 drops to the bottom of the chute where it may be engaged by the end 59 as the feed rod is moved in the opposite direction.

The blank feeding mechanism as designed in the present embodiment of my invention is adapted to not only feed the blanks to the work-carrying head, but also to restore the tapping tool 15 to its initial starting point, i. e., with the coupling which has been threaded while in the outer position of the work-carrying head, to be engaged by the rearmost set of blank gripping jaws, these jaws being the pair indicated at the right of Fig. 5. In carrying out the steps enumerated above the end 59 of the rod 54 engages the projecting end of the tap 15 as the blank is fed from the chute to the conduit 9, it of course being obvious that the jaws 20 will be at that time retracted through the actuation of slide 30. As constructed, in the threading operation of the tap, the forward end as it moves to the left of Fig. 5 serves to retract the feeding rod from the coupling being threaded, through its engagement with the reduced

projection 59. This retracted movement of the rod 54 serves, through the connection of the arm 57, to slide the shaft 58 which, as will presently appear, carries thereon a cam 103 adapted to actuate the mechanism for rotating the cam drum.

The tap holder and blank stripping mechanism.

As has been previously indicated the tap 15 is extended longitudinally of the machine and has its outer or free end detachably engaged by means for holding the same during the threading operation and the blanks as threaded are moved rearwardly along such tap shank toward the free end. At the rear end of the machine, upon guideways 62, provided on the top of bed plate extension 63, is slidably mounted a vertical bracket 64. Positioned in a longitudinal opening 65 in the bracket 64 is a spring pressed block 66 having its forward side suitably apertured at 67 in alignment with the end of the tap 15. This aperture 67 and the end of the tap may be provided with any formation of interlocking members, in the form shown the tap having a squared end thereon and the aperture 67 formed accordingly.

Referring to the diagrammatic Figures 12 to 15, inclusive, the sequential steps of the various operating elements are illustrated in the performance of one complete cycle in the operation of the machine. In these figures the block 66 is shown as being connected to the tap 15 at the initial starting point of the threading operation and to remain in such connected relationship until the tap has completed the threading of the foremost article in the work-carrying head 9. At this time the block 66 is retracted toward the outer end of the machine and other mechanisms function to discharge the blanks which have arrived at the outer end of the tap. While the block is disengaged with the tap and the stripping mechanism is operating to discharge the blanks from the end of the tap the jaws 20 are retained in engagement with the blanks in the head 9. Subsequent to this step the jaws are open and a new blank inserted in the head 9 through the reciprocation of rod 54 which, as has been described, serves to move the tap rearwardly of the head 9. This rearward movement of the tap acts to re-engage the outer end thereof with the block 66. During the feeding of the coupling to the work-carrying head the tap is maintained in alignment in the spindle 8 through the engagement of the completed couplings which are held within the bore 14 of such spindle. At the start of the operation of the machine, that is, when first setting up for a new job, there are no couplings within the bore 14 and therefore the outer end of the tap is not supported through the bearing of such couplings with the spindle.

To overcome this feature I have provided in the stripping mechanism spring pressed fingers 69 which project inwardly and serve to engage the tap.

The fingers 69 are, as mentioned, provided at the interior of a stripper block 70 which is centrally bored and carried about the rear end of the tap. The shaft 58 extends from end to end of the machine and is supported above the bracket 64 in a journal boss 71 secured thereto. Means for supporting the stripper block 70 consists of an arm 72 engaged about the shaft 58 and secured to the bracket 64 by means of a rod 73. The shaft 58 is slidably received within the journal 71 so that the movement of such shaft will not affect the position of the bracket 54.

The cam drum mechanism

The main drive shaft of the machine, which has been designated hereinbefore by the numeral 5, is adapted, through the engagement of the worm 6 and worm wheel 7, to continuously rotate the spindle shaft 8 so that in the operation of the machine the work-carrying head 9 is continuously rotated. It is the purpose of the present invention to provide a cam drum or like mechanism which is intended to actuate, through suitable connections, the blank feeding rod 54, the blank gripping jaw operating yoke 41 and the tap engaging block 66. This cam drum 10 is positioned at one side of the bracket 4 to surround the spindle 8 and has mounted on its outer periphery cam plates 75 and 76 which engage with the cam rolls provided on certain mechanisms connected to the shaft 58 and to the bracket 64. In the present disclosed embodiment the cam 10 is rotated intermittently at the completion of each cycle of operation of the machine, i. e., the same is held stationary during the threading operation and is effective only during the actuation of the blank feeding and stripping devices.

Referring to Figs. 3 and 7, I have shown at 77 a sleeve mounted to turn on the spindle 8 within the cam drum 10. This sleeve has formed at its rear end external gear teeth 78 which mesh with a plurality of pinions 79 mounted about pins 80 within the cam drum and engaging with the internal gear teeth 81. The gear teeth may be formed integral with the cam drum 10 or of a separate ring member secured thereto. This construction provides for a planetary gear arrangement so that as the sleeve 77 is rotated with the spindle 8 the cam drum 10 will be rotated in the reverse direction and at a much lesser rate of speed. However, as stated hereinbefore, the cam drum 10 is only intended to be rotated one complete revolution during each cycle of operation of the machine and therefore the sleeve 77 is engaged with the spindle 8 only at such times.

65 The forward end of sleeve 77 is enlarged at

83, and secured to the spindle 8 adjacent the enlarged portion 83 is an annular collar or ring 84. Means in the form of a sliding latch 85, carried in a recess in the sleeve 77, is provided to intermittently engage such sleeve 70 with the collar 84, and thereby cause the rotation of the drum 10. A vertical bracket or guide block 86 is secured to the rear end of a vertical standard 4 having apertures 87 and 88 therein to receive the shaft 58 and the collar 84, respectively. Formed in the rear face of the guide block 86 are vertical guide-ways 88', in which is mounted for vertical reciprocation a cam latch member 89 having its lower end provided with means adapted 80 to cooperate with the latch 85 to retain said latter member in retracted position, i. e., out of engagement with the collar 84. A compression spring 90, received in a longitudinal aperture 91 formed in the sleeve 77 85 in alignment with the recess 92, is provided to engage the rear end of latch 85 to keep such member normally pressed toward the collar 84. The outer periphery of the enlarged portion 83 of sleeve 77 is formed with 90 an encircling groove 93, in which the lower end of the vertical latch 89 is adapted to be received. The groove 93 communicates with the recess 92 to permit the latch 89 to engage with a recess 94 formed in the outer side of 95 the latch 89. It will be apparent from the foregoing that while the lower end 95 of latch 89 is engaged with the recess 94 the cam drum will not rotate, and that upon freeing the end 95 from engagement with the latch 85 the latter member will be engaged, through the action of spring 90, with the collar 84 secured to the spindle 8 and consequently the drum will be rotated.

In carrying out the function of the various elements controlled through the cams mounted on the cam drum 10 it is only necessary to rotate such drum one complete revolution, and therefore the latches 85 and 95 have been so designed that they operate automatically to disengage the drum with the driving spindle 8 at each complete rotation of the drum. In Fig. 6 the latch member 85 is shown in retracted position. Assuming now that the latch 89 is lifted to permit latch 85 to engage the drum with the spindle 8 the sleeve 77 will be caused to rotate in the direction of the arrow, indicated in such figure. In Fig. 8 the lower end of latch 89 is illustrated as being formed with an inclined cam face 96 980 which engages with an inclined surface 97 formed at one side of recess 94 to retract the latch 85 as said latter member is again carried by the sleeve into contact with the latch 89.

Suitable mechanism in the form of a rock shaft 98, mounted in bearing 99 and having secured thereto a laterally extending arm 100, is provided to effect the raising of latch member 86 at the completion of the thread-

ing operation. This rockshaft 98 is actuated to lift the latch member 89 to permit the engagement of the drum 10 with the driving spindle 8 and to thereafter lower the latch so that the same will ride in the groove 93 in position ready to disengage the latch 85 as that member is carried by the sleeve 77 in its rotation, as has been described.

10 *The operating shaft 58*

The shaft 58, which extends from end to end of the machine and is slidably mounted in brackets 3, 4 and 71, carries thereon the arm 57 which actuates the feeding rod 54, 15 the arm 72 connected to the stripping mechanism, spaced adjustable collars adapted to engage the jaw operating yoke 41, a cam member adapted to actuate the rockshaft 98, and an arm 101 fixed thereto and carrying 20 at its lower end a cam roll 102 in the path of the cams 75 and 76 on the drum 10.

In the operation of the machine as the threading tool or tap 15 is moved outwardly through the work-carrying head, such tool 25 forces the blank feeding rod 54 to the left of Fig. 2. This movement is transmitted to the shaft 58 and at the time the threading operation has been completed the cam 103 has been moved to engage with an arm 104 secured to the rockshaft 98. Through this 30 engagement the rockshaft is rotated and the latch 89 raised to permit the connection of the cam drum to the driving spindle. A complete description has been given herein- 35 before of the sequential steps in the operation of the blank feeding rod, the blank gripping jaws in the work-carrying head, the tap holder and the stripping mechanism, all of which devices are controlled through 40 the reciprocation of shaft 58 after the cam drum is set in motion. The first function of the cam drum in its rotation is to retract the block 66 to the left of Fig. 1 to disengage the same with the end of the tap, suit- 45 able mechanism being provided in the form of a link 106 secured at one end by a pin 107 to the sliding standard 64 and at its other end to the outer end of a pivoted arm 108. The arm 108 is mounted about a stud 50 109 on the bed plate of the machine, and carries at its outer end a cam roll 110 in line with the cams 75 and 76 on the drum 10. The shaft 58 is slidable within the journal 71, which latter member is secured to the head 55 66, and as the head 66 is actuated by the cam 75 the shaft 58 remains stationary. Sub- 60 sequent to the disengagement of the tap holder with the tap 15 the cams on drum 10 engage the roll 102 and effect the reciprocation of shaft 58. The first part of the movement of shaft 58 causes one of the collars 111 to contact with the projection 43 on the yoke 41 and thus move the slide 30 to the left to Fig. 5 to disengage the jaws 20 with 65 the blanks carried in the head 9. Further

movement of the shaft 58 places the end 59 of the rod 54 in position to feed a fresh blank. At this time the cams on the drum 10 cause the shaft 58 to move to the right of Fig. 2 and thus carry the blank held in 70 the lowermost position of chute 50 to the work-carrying head 9. This movement, as has been described, not only carried out the feeding function, but also retracts the tap in the initial starting position and engages 75 the outer end thereof with the holding block 66. Immediately after the tap has been restored to starting position another of the collars 111 actuates the yoke 41 to close the work-gripping jaws 20 on the blanks in the 80 head 9. At this time the cam drum has made one complete revolution and the inclined surface 96 has withdrawn the latch 85 from engagement with the collar 84 and the drum ceases to rotate.

It will be apparent from the foregoing that I have accomplished the objects primarily stated and that I have provided a new and improved machine which continuously and automatically threads couplings or like articles, one at a time, as they are fed to the machine. Each of the several operating elements in the construction of the present disclosed embodiment are adjustable one to the other, so that the machine may be regulated 95 to adapt the same for operation on articles of varying sizes or lengths of thread to be cut. While in such embodiment the work is held in a rotating holder and the threading tool is mounted stationary, this invention contemplates the construction of a machine wherein the work holder is non-rotatably mounted and the driving mechanism is detachably secured to the tap so that such latter member may be rotated relatively to the 100 work.

Other modes of applying the principle of my invention may be employed instead of the one explained, change being made as regards the means and the steps herein disclosed, provided those stated by any of the following 110 claims or their equivalent be employed.

I therefore particularly point out and distinctly claim as my invention:—

1. In a method of threading hollow articles, the steps which consist in intermittently feeding such articles to the first of two sets of aligned gripping jaws, axially moving a tap into the gripped article to cut threads on the interior thereof, and moving 120 said tap and threaded article to a position for engagement by the second set of gripping jaws, said last step being performed simultaneously with the feeding operation.

2. In a method of threading hollow articles, the steps which consist in threading a tap into one of such articles, gripping such threaded article whereby further relative rotation of the tap and said article will cause longitudinal movement of the tap, feeding 125

a second article into axial alignment with said first-named article, gripping such second article and threading the same upon said relative rotation between said first article and the tap.

5. 3. In a method of threading hollow articles, the steps which consist in intermittently feeding such articles to the first of two sets of aligned gripping jaws, axially moving a tap into the gripped article to cut threads on the interior thereof, supporting the rear end of the tap during the threading operation, and moving said tap and threaded article to a position to be gripped by the second set of gripping jaws, said last step being performed simultaneously with the feeding operation.

4. In a method of threading hollow articles, the steps which consist in intermittently feeding such articles to the first of two sets of aligned gripping jaws, axially moving a tap into the gripped article to cut threads on the interior thereof, supporting the rear end of the tap during the threading operation, moving said tap and threaded article to a position to be gripped by the second set of gripping jaws, and releasing said gripping jaws during said feeding operation.

5. 5. In a method of threading hollow articles, the steps which consist in moving a tap through said articles, intermittently feeding one article at a time to the first of two sets of aligned gripping jaws, threading said tap partially through said gripped article, and moving said tap with said partially threaded article to a position for engagement by said second set of jaws, said last step being performed simultaneously with said feeding operation.

6. 6. In a method of threading hollow articles, the steps which consist in presenting blanks in coaxial alignment with a straight tap, gripping two of said blanks in alignment, passing the tap entirely through one and partially through the other of said gripped blanks, releasing the gripping mechanism, retracting said tap and partially threaded blank to discharge the threaded blank through said gripping mechanism, and feeding an unthreaded blank to said gripping mechanism simultaneously with said last-named step.

7. In a method of threading hollow articles, the steps which consist in holding two such articles in alignment with a threading tool, one of said articles being threaded and having engagement with the thread cutting portion of said tool, and in revolving the holding means to feed said tool through the threaded article and to cut threads on the interior of said other article.

8. Threading mechanism comprising a work-carrying head, two sets of axially aligned gripping jaws mounted therein, a

tap movable axially of said jaws, means for intermittently feeding blanks to one set of jaws, and means for rotating said head, said tap serving as a means to transfer work from said one set of jaws to the other.

9. Threading mechanism comprising a work-carrying head, two sets of gripping jaws mounted therein, a tap movable axially of said jaws, means for feeding blanks to one set of said jaws, means for rotating said head to thread the tap into such engaged blank, and means for retracting said tap together with the blank threaded thereon in position for engagement with the other set of said jaws.

10. In a machine of the character described, the combination of a hollow spindle, a tap having threaded elements at one end, said tap being located interiorly of said spindle and unsupported thereby, a work-carrier mounted on said spindle, disengageable work-gripping mechanism carried thereby, means for detachably engaging the shank end of said tap, and means for relatively revolving said carrier and tap.

11. In a machine of the character described, the combination of a hollow rotatable spindle, a tap having threading elements at one end, said tap being located interiorly of said spindle and unsupported thereby, a work-carrier mounted on said spindle, disengageable work-gripping jaws carried thereby, means for intermittently feeding blanks to said jaws, and detachable means for engaging the shank end of said tap.

12. In a machine of the character described, the combination of a hollow spindle, a work-carrying head mounted thereon, gripping jaws carried by said head, means for opening and closing said jaws, a tap having threading elements at one end, said tap being located interiorly of said spindle and unsupported thereby, means for intermittently feeding blanks to said head, means for detachably engaging the shank end of said tap, and means for relatively revolving said carrier and tap.

13. In a machine of the character described, the combination of a drive shaft, a hollow spindle, means for rotating said spindle from said shaft, a work-carrying head mounted on said spindle, gripping jaws carried by said head, means for opening and closing said jaws, a tap having threading elements at one end, said tap being located interiorly of said spindle and unsupported thereby, means for intermittently feeding blanks to said head, and means actuated from said drive shaft for effecting the operation of said gripping jaws and said feeding means.

14. In a machine of the character described, the combination of a drive shaft, a hollow spindle, means connecting said spindle to said shaft for revolving the former, a work-carrying head mounted at one end of said

- spindle, a plurality of sets of gripping jaws carried by said head, an axially aligned tap adapted to co-operate with said head to thread blanks carried by the latter, means for intermittently feeding blanks to one of said sets of jaws, and means operated by said feeding means adapted to open said jaws to release the blanks engaged thereby, said tap serving as a means to transfer blanks from said one set of jaws to another.
15. Threading mechanism comprising a work-carrying head, outer and inner sets of aligned gripping jaws mounted therein, means for intermittently feeding blanks to the outer set of said jaws, an axially aligned tap adapted to thread the gripped blanks, and means for transferring the blank from the outer set of jaws to the other set of jaws.
16. Threading mechanism comprising a work-carrying head, outer and inner sets of aligned gripping jaws mounted therein, means for intermittently feeding blanks to the outer set of said jaws, an axially aligned tap adapted to thread the gripped blanks, and means including the feeding means for transferring the blank from the outer set of jaws to the other set of jaws.
17. Threading mechanism comprising a work-carrying head, outer and inner sets of aligned gripping jaws mounted therein, means for intermittently feeding blanks to the outer set of said jaws, an axially aligned tap adapted to thread the gripped blanks, and means including the feeding means and said tap for transferring the blank from the outer set of jaws to the other set of jaws.
18. Threading mechanism comprising a work-carrying head, outer and inner sets of aligned gripping jaws mounted therein, means for intermittently feeding blanks to the outer set of said jaws, an axially aligned tap located interiorly of said head and unsupported thereby, said head and tap being actuated to thread the latter only partially through the blank gripped in said outer set of jaws, and means for transferring said tap and blank threaded thereon into position for engagement by said other set of jaws.
19. Threading mechanism comprising a work-carrying head, outer and inner sets of aligned gripping jaws mounted therein, means for intermittently feeding blanks to the outer set of said jaws, an axially aligned tap located interiorly of said head and unsupported thereby, said head and tap being actuated to thread the latter only partially through the blank gripped in said outer set of jaws, and means for transferring said tap and blank threaded thereon into position for engagement by said other set of jaws, said last named means being actuated in timed relation with said feeding means.
20. Threading mechanism comprising a rotatable work-carrying head, a plurality of sets of gripping jaws mounted therein, means for opening and closing said jaws, a tap located interiorly of said head and unsupported thereby, means for intermittently feeding blanks to one of said sets of jaws, and means connected to said feeding means adapted to actuate said jaw opening and closing means, said tap serving as a means to transfer blanks from said set of jaws to another.
21. In a tapping machine, a tap, mechanisms for longitudinally shifting the tap in two directions, means for gripping the work to be threaded by the tap, and means automatically operated by an advancing movement of the tap for initiating the actuation of said mechanisms.
22. In a tapping machine, a tap, mechanisms for longitudinally shifting the tap in two directions, means for gripping the work to be threaded by the tap, one of said mechanisms serving to operate the work gripping means and means automatically operated by an advancing movement of the tap for initiating the actuation of said mechanisms.
23. In a tapping machine, a tap, mechanisms for longitudinally shifting the tap in two directions, means for gripping the work to be threaded by the tap and means operated by one of said mechanisms for operating the gripping means.
24. In a metal cutting machine the combination of a cutting tool, means for holding work to be operated upon by said tool, means for effecting relative rotation between the work holding means and said tool, a camming mechanism coaxially arranged relative to said means for effecting a relative longitudinal movement between the work and tool and means for intermittently operatively connecting said rotation means to the camming mechanism.
25. In a metal cutting machine the combination of a cutting tool, means for holding work to be operated upon by said tool, means for effecting relative rotation between the work holding means and said tool, a camming mechanism coaxially arranged relative to said means for effecting a relative longitudinal movement between the work and tool, a clutch mechanism for connecting the camming mechanism to the rotation means, and means for operating the clutch mechanism and controlled by said relative longitudinal movement effected between the work and tool.
26. In a metal cutting machine the combination of a cutting tool, means for holding work to be operated upon by said tool, means for effecting relative rotation between the work holding means and said tool, a camming mechanism coaxially arranged relative to said means for effecting a relative longitudinal movement between the work and tool and a clutch mechanism intermittently operated by the camming mechanism.

27. In a metal cutting machine the combination of a cutting tool, means for holding work to be operated upon by said tool, means for effecting relative rotation between the work holding means and said tool, a camming mechanism coaxially arranged relative to said means for effecting a relative longitudinal movement between the work and tool, means for intermittently operatively connecting said rotation means to the camming mechanism, said last named means being controlled by said relative movement between the work and tool.

28. In a metal cutting machine the combination of a cutting tool, means for holding work to be operated upon by said tool, means for effecting relative rotation between the work holding means and said tool, a camming mechanism coaxially arranged relative to said means for effecting a relative longitudinal movement between the work and tool, means for intermittently operatively connecting said rotation means to the camming mechanism and means for automatically removing work from the work holding means.

29. In a metal cutting machine the combination of a cutting tool, means for holding work to be operated upon by said tool, means for effecting relative rotation between the work holding means and said tool, a camming mechanism coaxially arranged relative to said means for effecting a relative longitudinal movement between the work and tool, a clutch mechanism for connecting the camming mechanism to the rotation means, means for operating the clutch mechanism and controlled by said relative longitudinal movement effected between the work and tool, and means for automatically removing the work from the work holding means.

30. In a metal cutting machine the combination of a cutting tool, means for holding work to be operated upon by said tool, means for effecting relative rotation between the work holding means and said tool, a camming mechanism coaxially arranged relative to said means for effecting a relative longitudinal movement between the work and tool, a clutch mechanism for connecting the cam-

ming mechanism to the rotation means, means for operating the clutch mechanism and controlled by said relative longitudinal movement effected between the work and tool, means for automatically removing work from the work holding means and other means for automatically feeding new work to the tool.

31. In a metal cutting machine the combination of a cutting tool, means for holding work to be operated upon by said tool, means for effecting relative rotation between the work holding means and said tool, a camming mechanism coaxially arranged relative to said means for effecting a relative longitudinal movement between the work and tool, a clutch mechanism for connecting the cam-

ming mechanism to the rotation means and means for operating the clutch mechanism and controlled by said relative longitudinal movement effected between the work and tool.

32. The method of forming internal threads in hollow articles, comprising holding an internally threaded article and a hollow blank in axial alignment, and presenting such aligned articles to a thread cutting tool in such manner that the tool acts on the blank while the already threaded article by engaging thread cutting portions of the tool forms a lead screw therefor.

33. The method of tapping hollow articles, which consists in holding two of such articles in coaxial alignment with a tap so that the tap passes through two articles successively, utilizing the first threaded article as a lead screw for tapping the second article, and thereafter causing the first threaded article to pass onto the shank of the tap and gripping the second article as a lead screw and an aligned third article as a blank to be threaded.

34. A threading mechanism comprising a work-carrying head, gripping jaws mounted therein, means for opening and closing the jaws, a tap located coaxially of the head, means for causing relative rotation between the head and tap, means for intermittently feeding blanks to said jaws, and means for connecting with said feeding means adapted to actuate said jaw opening and closing means.

35. The method of forming threads on articles, comprising holding a previously threaded article and a blank in alignment, and presenting such aligned articles to a thread-cutting tool in such manner that the tool acts on the second article, while the first article forms a lead screw for the tool.

36. Threading mechanism comprising a work-carrying head, two sets of axially aligned gripping jaws mounted therein, a tap movable axially of said jaws, the head and tap cooperating, and there being means for rotating one of them, and means for intermittently feeding blanks to the outer set of jaws.

37. Threading mechanism comprising a work-carrying head, two sets of gripping jaws mounted therein, a tap movable axially of said jaws, means for feeding blanks to one set of said jaws, means for causing a relative rotation between said head and tap to thread the tap into such engaged blank, and means for retracting said tap together with the blank threaded thereon in position for engagement with the other set of said jaws.

38. Threading mechanism comprising a work-carrying head, two sets of aligned gripping jaws mounted therein, means for intermittently feeding blanks to the outer set of said jaws, a tap axially aligned with the

head, and one of them being rotated to thread the tap partially through the blank gripped in said outer set of jaws, and means for transferring said tap and blank threaded thereon into position for engagement by said other set of jaws.

39. Threading mechanism comprising a work-carrying head, two sets of aligned gripping jaws mounted therein, means for intermittently feeding blanks to the outer set of said jaws, a tap axially aligned with the head, and one of them being rotated to thread the tap partially through the blank gripped in said outer set of jaws, and means for transferring said tap and blank threaded thereon into position for engagement by said other set of jaws, said last named means being actuated in timed relation with said feeding means.

20 Signed by me, this 22nd day of June, 1927.
JAMES F. PATTON.
